WISCONSIN, A CORPORATION OF WISCONSIN.

MACHINE-TOOL ORGANIZATION.

Application filed January 18, 1926. Serial No. 82,066.

This invention relates to a machine tool organization and particularly to an improved structure for housing and supporting a rotatable spindle and its drive mechanism.

5 A main purpose is to provide a driving mechanism completely housed within the main structure of the machine, together with simplified lubricating devices therefor.

Another purpose is generally to simplify 10 and improve the construction, arrangement and operation of a machine tool, and to promote the safety of the operator.

Other purposes will be apparent from the accompanying drawings, description and 15 claims.

In the drawings, like reference characters are used to denote the same parts in the different views, of which

Fig. 1 is a left side elevation of a milling 20 machine of the knee and column type, embodying the invention. A portion of the view is shown as a section taken along line 1—1 of Fig. 2, and some of the well known parts of a complete milling machine have been omitted.

25 Fig. 2 is a rear elevation of the same machine.

A main support or column 1 rotatably supports a tool spindle 2 journaled in a front wall 3 and a rear wall 4 with the spindle ends 30 projecting outside these walls for various purposes. A plurality of overarms 5 and 6 are likewise supported by the column and are slidably mounted to be shoved forward, if required for supporting the ends of a tool arbor 35 and for other reasons, or to be shoved to the rear when not required so as to be out of the way of the operator. A knee or work support 7 is vertically slidable on front wall 3. Other relatively movable work supports, such as a 40 saddle and a table are ordinarily supported by the knee but the construction of such supports being well known they are not shown in the drawings. Combined with the front and rear walls 3 and 4 are left and right side walls 8 45 and 9, also a bottom wall 10 and a top wall 11 to provide a hollow box-like form for the column. A horizontal rib or wall 12 in combination with other wall portions form a chamber 13 in the base of the column which 50 chamber is intended to hold cutting fluid used to cool cutters and work or for similar purposes. Motor 14 is removably fixed on the top of rib 12.

A chamber 15 is formed in an upper por-

tion of the structure by portions of front, 55 rear, top and right and left hand walls and by a rib or wall 16 which extends from one to the other of the side walls and is spaced sufficiently distant from the horizontal wall 12 to provide sufficient vertical space for a motor 14. 60

Portions of various of the walls described above together with a substantially vertical rib or wall 17 form a chamber generally denoted by the numeral 18, within which motor 14 is housed, the chamber having an opening 65 to the rear for removal of the motor, which is normally closed by a removable cover 19 which is held in place by suitable screws or may be hinged. The wall 17 is spaced sufficiently far from the front wall 3 to form, together with a bottom wall 20^a and portions of the front and side walls, a lubricant chamber 20 communicating with the upper chamber 15, and adapted to house a portion of the mechanism as will be described. 70

Cover 19 has a series of openings 19^a, serving to permit a large volume of air to pass into chamber 18 while excluding even comparatively small solid objects. The location and form of openings 19^a prevents oil or other 75 fluid which might run down the rear wall 4 from passing into the chamber 18.

An opening 21 in chamber 18 is covered with a removable plate 22 having a series of openings 22^a formed by downward slanting 80 portions 22^b. These openings are above the level of the openings 19^a and serve to discharge air which has been drawn in at lower openings 19^a and heated through the operation of motor 14. A continuous circulation of 85 air to ventilate and cool the motor is thus assured.

Spindle 2 is driven from motor 14 by the following transmission mechanism. A pinion 23 is keyed to motor shaft 24 and projects into the chamber 20. The shank portion 23^a is provided with annular grooves 23^b which serve to prevent lubricant from moving along the shank portion, such lubricant being thrown off or dripping from the high portions of the grooves, into a circular chamber or groove 25^a in a bushing 25, surrounding the shank 23^a, and from which lubricant is returned to the chamber 20 by the means of an opening 25^b. Meshed with the pinion 23 is intermediate gear 26 fixed on short shaft 27, the respective ends of which are journaled in 90 a bushing 28 fixed in the wall 17, and in the 95 100 105

front wall 3. Shaft 27 passes through and drives a lubricant pump 29 which is fixed on front wall 3, and which may be a pump of the enclosed gear type or of any other suitable type. A clutch member 30 is provided with a shank 30^a rotatably supported in front wall 3. An axial bore of sleeve 30^a forms a bearing for the one end of a shaft 31, the other end of the shaft being journaled in a rib 31^b of the column 1. A clutch member 32 is slidably keyed to shaft 31 and has a shank or extension 32^b provided with an annular groove 32^a. A hand lever 33 is fixed to the outer end of a short shaft 34, pivoted 10 in a suitable bearing in the wall 8. A fork 36 is fixed to inner end of shaft 34 and carries pivoted shoes 36^a engaging with the annular groove 32^a. By the mechanism described the clutch member 32 may be shifted by the movement of hand lever 33 in the one or the other direction to engage or disengage the complementary friction surfaces of the members 30 and 32 whereby shaft 31 may be engaged or disengaged from motor 14. A pinion 31^a is 20 fixed on or integral with shaft 31 and meshes with a gear 37 keyed to a shaft 38 rotatably supported from column 1.

Shaft 38 may drive a shaft 45 rotatably supported from column 1, through a speed 30 change mechanism consisting of gears 39, 40, 41, slidably keyed on shaft 38 and respectively engageable one at a time with the gears 42, 43, 44 fixed on shaft 45. Also fixed on shaft 45 is a pinion 46 meshing with gear 47 fixed on 35 spindle 2. The several gear pairs 39 and 42, 40 and 43, 41 and 44, are of different ratio and as the gears 39, 40, 41 are shifted to engage with the complementary gears, the speed of shaft 45 and of spindle 2 is correspondingly 40 changed. Gears 39, 40 and 41 are fixed together to be shifted simultaneously by the means of a hand lever 48, Fig. 2, fixed on the outer end of a short shaft 49 pivoted in wall 8 and having fixed on its inner end a 45 lever 50 connected to move the gear set by means of fork 51 engaging the sides of gear 40 and pivoted in lever 50.

The pump 29 is driven whenever any portion of the machine is operated. The chamber 20 is supplied with lubricant into which a suction pipe 52 dips, and is connected to the suction part of the pump. A pipe 53, connected with the discharge part of the pump elevates the lubricant to an upper level of 55 the chamber 15 and there communicates with a pipe or header 54 provided with openings 54^a adapted to spray the lubricant over the interior of the walls of chamber 15 and over the gearing contained therein, the motion of 60 the gears assisting together with the openings 54^a to more or less completely fill the chambers 15 and 20 with flying drops of lubricant. Each of the various bearings associated with the walls of both the chambers 65 are provided with open pockets adapted to

receive some of the flying drops of lubricant, either directly or as they flow down the sides of the walls, one of the pockets being shown at 55. Each of the pockets communicates with its bearing by means of a suitable hole 70 as shown at 56 for the pocket 55.

Substantially all of the lubricant elevated from the reservoir in chamber 20, after passing through the chamber 15, eventually returns to the reservoir to be again elevated, 75 thus providing a continuous circulation of lubricant between the reservoir and each of the moving parts of the transmission mechanism.

Any lubricant which may enter the motor 80 chamber 18 in spite of precautions described above will collect on the lower wall 12 and pass through opening 61 into the coolant chamber 13 to mix with the fluid therein where it will do no harm. It will be apparent 85 that the quantity of such lubricant will be very small.

The above taken in connection with the drawings clearly describes a preferred form of the invention for which a patent is desired 90 and for which a variety of other but equivalent forms may be constructed in the light of this disclosure. Patent protection is desired for each of the various forms of the invention within the spirit and scope of the accompanying 95 claims.

We claim:

1. In a machine tool the combination of a column structure having upstanding side and end walls cooperating with other walls 100 to form an upper chamber, a motor chamber formed in part by some of said walls at a lower level of said structure and substantially underneath said upper chamber, a motor enclosed within said motor chamber, speed change gearing enclosed within said upper chamber, a transmission train connecting said speed change gearing to be driven from said motor, a lubricant reservoir located in a lower level of said structure, a pump, 110 a lubricant channel leading from said reservoir to an upper level of said structure and passing through said pump, a header adapted to distribute lubricant from said channel to said speed change gearing and a closed passage for the return of lubricant to said reservoir, a substantial portion of the walls of said motor chamber forming wall portions of said closed passage.

2. In a milling machine the combination of 120 a column structure having upstanding side and end walls cooperating with other walls to form an upper chamber, a spindle journaled in said walls to pass through said chamber and having projecting end portions, a 125 speed change mechanism enclosed within said chamber and connected with said spindle, a motor chamber formed in part by some of said walls at a lower level of said structure and substantially underneath said upper chamber 130

ber, a motor housed within said motor chamber, a transmission train connecting said motor and said speed change mechanism, a lubricant reservoir, a pump, a header for supply of lubricant to said speed change mechanism and spindle, a lubricant channel connecting said header to be supplied with lubricant under pressure from said reservoir by

the means of said pump, and a closed channel for the return of lubricant to said reservoir from said header, wall portions of said upper chamber and of said motor chamber being in heat transferring contact with said lubricant. 10
